FOOT BALANCER INSERT

Dale Wendell Austin, Los Angeles, Calif.

Application October 10, 1949, Serial No. 5,400

Term of patent 14 years

(Cl. D7—3)

To all whom it may concern:

Be it known that I, Dale Wendell Austin, a citizen of the United States, residing at Los Angeles, in the county of Los Angeles, State of California, have invented a new, original, and ornamental Design for a Foot Balancer Insert, of which the following is a specification, reference being had to the accompanying drawing, forming a part hereof.

Figure 1 is a perspective view generally in plan of a foot balancer insert embodying my new design;

Fig. 2 is a top plan view of the insert disclosed in Fig. 1;

Fig. 3 is a bottom view of the insert;

Fig. 4 is a side view of the insert taken in the direction of the lines 4—4 in Fig. 2; and

Fig. 5 is an end view of the insert taken in the direction of the lines 5—5 in Fig. 2.

I claim:

The ornamental design for a foot balancer insert, as shown.

DALE WENDELL AUSTIN.
